UNITED STATES PATENT OFFICE.

LEE R. ROGERS, OF CHICAGO, ILLINOIS, ASSIGNOR TO UNDERWOOD TYPEWRITER COMPANY, OF NEW YORK, N. Y., A CORPORATION OF DELAWARE.

STENCILING-MACHINE.

1,237,820.

Specification of Letters Patent. Patented Aug. 21, 1917.

Application filed March 17, 1914. Serial No. 825,194.

To all whom it may concern:

Be it known that I, LEE R. ROGERS, a citizen of the United States, residing in Chicago, in the county of Cook and State of Illinois, have invented certain new and useful Improvements in Stenciling-Machines, of which the following is a specification.

My invention relates to mimeographs or duplicating machines in which a series of work sheets are fed *seriatim* to a stencil cylinder, the work sheets being fed between the cylinder and the feed roll. In machines of this character, it is customary to supply ink through an inking pad and stencil sheet wrapped on the surface of the cylinder for printing on the work sheets as they are fed over the cylinder. When the supply of work sheets is exhausted, or if for any other reason the sheets are not supplied to the cylinder, the feed roll is apt to run directly in contact with the inking portions of the cylinder and becomes smeared with ink which is transmitted to succeeding work sheets.

The primary object of my invention is to provide simple and effective means to overcome this objection, and to this end, provision is made for automatically lifting the feed roll from the cylinder whenever the supply of work sheets fails, the mechanism for lifting the feed roll being controlled by the work sheets. The feed roll may be carried by a swinging frame and held against the cylinder by means of a cam or other suitable mechanism held in operative position by a latch. The latch may be released when the supply of work sheets fails, by a trip device which is reciprocated, as by means of an eccentric geared to rotate in unison with the cylinder. When the work sheets are being normally fed forward to the cylinder, the trip device is deflected by the sheets to an inoperative position, but whenever the supply of work sheets fails, the trip device is permitted to release the latch, and thereby cause the feed roll to be lifted from the cylinder. A cam on the cylinder shaft may automatically restore the mechanism including the latch for holding the feed rolls against the cylinder.

Other objects of the invention will hereinafter appear.

In the accompanying drawings, which

illustrate one form of my invention, Figure 1, is a perspective view of an Underwood revolving duplicator with the present improvements.

Fig. 2 is a view of the latch, and a trip device for actuating the latch.

Fig. 3 is a sectional view of the mechanism shown in Fig. 2.

Fig. 4 is a part sectional side elevation view showing the latch in released position, and the feed roll lifted from the cylinder. In this view the cam on the cylinder shaft is coming into position to restore the latch, and the work sheet which is also being fed forward has just engaged the trip to move it to an ineffective position, and permit the latch to be restored.

Figs. 5 and 6 are diagrammatic views of the mechanism shown in Fig. 4, but with the parts in different positions. Fig. 5 shows the cylinder advanced beyond the point at which the cam has restored the pressure roll, and the latch in holding position. Fig. 6 shows the position of parts with the supply of work sheets exhausted, and just after the trip device has operated to release the latch.

The usual stencil cylinder 1 mounted on an axle 2 is rotated either manually or otherwise. A gear wheel 3 is rotatable with the cylinder, and through an intermediate pinion 4, rotates a gear wheel 5 fixed to a hollow sleeve or axle 6 to which are secured paper feeding segments 7. The gears 3, 4, and 5 are preferably of the same diameter so that each rotation of the cylinder imparts a complete rotation to each gear and also to the feeders 7. The axle 6 may be mounted on a tie rod 8, connected to swinging arms 9 to form a swinging frame for lifting the feeders 7 away from the work sheets 10. The pile of work sheets 10 is supported on a table 11 pressed upward by springs, (not shown), so that the uppermost sheet is in position to be moved forward when engaged by the feeders 7. Side gages 12, and a rear gage 13 bear against the edges of the work sheets, and are adjustable to accommodate sheets of different sizes.

At each rotation, the feeders 7 frictionally engage a work sheet 10 and feed it forward, until the leading edge is gripped between

the rotating stencil cylinder 1 and a feed roll 14, which may be the usual soft rubber feed roll supported on arms 15 connected at their forward ends to pivots 16. The free ends of the arms 15 are connected by a cross bar or roller 17, which is normally held up by a cam 18 to cause the roller 14 to bear against the cylinder or the work sheet thereon. The cam 18 is fixed to a rock shaft 19, to which is also fixed a rock arm 20 carrying a pivoted rod 21, extending upward into position to be actuated by a cam 22 adjustably secured to the cylinder axle 2 as by means of a nut 22a. A spring 23 tends to rotate the cam 18 downward into position to permit the feed roll 14 to drop away from the stencil cylinder, but such rotation of the cam is normally prevented by a latch 24 pivoted at 25 and having a detent to engage a notch 26 in the holding rod 21, as shown in Fig. 5. The rod 21 is supported and guided by a guide roll 27 on the machine frame.

During the normal operation of the machine, the latch 24 remains in engagement with the rod 21, and the feed roll 14 is maintained in operative position. When, however, the supply of work sheets 10 is exhausted, or for any other reason the feeders 7 fail to advance a sheet to the cylinder, the latch 24 is released to permit the feed roll 14 to drop, and thereby prevent the roll from becoming smudged or daubed with ink from the cylinder. The mechanism for releasing the latch is as follows:

Secured to the inner face of the gear wheel 4, is an eccentric disk 28, which drives an eccentric ring 29 having a depending arm 30 adapted to strike the inturned end 31 of an arm 32, projecting from the latch 24. Each rotation of the gear wheel 4 imparts an up-and-down movement to the trip arm 30, and said arm is guided during such movement by means of flanges 33 on said arm, embracing the end of a guide rod 34, projecting downward from a horizontal rock shaft 35 to which is also secured an arm 36, projecting downward into the path of the work sheets 10. The lower end of the arm 36 may project into a guiding slot 37 formed in a plate 38 over which the work sheets are slid in their passage from the feeders 7 to the cylinder.

Each work sheet, as it moves forward strikes the rod 36 and rocks the shaft 35 so that the arm 34 thereon, carries the trip 30 forward beyond the end of the latch arm 32 so that the trip 30, when moved downward by the eccentric, does not operate the latch. When, however, the feeders 7 fail to advance a work sheet, owing to the supply being exhausted, or for any other reason, the arm 36 is not moved forward and the trip arm 30, therefore, in its descent, strikes the latch arm 32 and operates the

latch 24, permitting the feed roll 14 to be 65 lifted from the cylinder, as before pointed out.

When the arm 36 has been released by a work sheet being carried beyond said arm, it is returned by the frictional turning moment 70 applied by the gear 4 to the shaft 35, the end of which, as shown in Fig. 3, is seated in the hub of said gear. This return movement may also be assisted by gravity, or a spring 75 might be used for this purpose, if desired. The movement ceases when the end of arm 36 engages the rear end of the slot. See Fig. 6.

As the stencil cylinder rotates after the pressure roll has been released, the cam 22 80 is brought to bear on the anti-friction roll 21a, depresses the rod 21 and restores the feed roll. The latch rod 21 is moved downward by the cam 22 far enough to permit the latch to be snapped into holding position by a spring 39, thus automatically restoring the parts to normal position.

It will be noted that the cam 22 is so positioned and the parts so timed that when the work sheets are exhausted, if the rotation 90 of the cylinder is continued, the feed roll is held off the cylinder through the greater portion of each rotation. Thus, as shown in Fig. 6, the trip 30 has just operated to release the latch, and as the cam 22 is only a short distance beyond the rod 21, the latter will not be again depressed to return the pressure roll 14 to the cylinder until the latter has made nearly a complete revolution from the Fig. 6 position.

If the movement of the cylinder is continued through one or more revolutions after the work sheets are exhausted, the latch mechanism will be reset during each revolution, and the pressure roll permitted to run on the cylinder during a fraction of a revolution. The portion of the cylinder, however, with which the pressure roll is thus engaged, is not supplied with ink, being in advance of that portion of the stencil sheet or surface through which ink is supplied to the work sheets. The feed roll is thus at all times kept free from the inking surface.

Variations may be resorted to within the scope of the invention, and portions of the 115 improvements may be used without others.

Having thus described my invention, I claim:

1. In a stenciling machine, in combination means comprising a latch to hold the feed roll in operative position, a trip device geared to the cylinder and operated during each rotation of the cylinder, a guide for said trip to cause it to move into position to release the latch and thereby cause the feed roll to be lifted from the cylinder, and a deflecting arm connected to said guide and projecting into the path of the work-sheets 120 125

whereby the trip device is deflected to inoperative position, and thus prevented from releasing said latch except upon the failure of the feeding mechanism to advance a work-sheet.

5. In a stenciling machine, the combination with a stencil cylinder, a feed roll running thereon, and mechanism to feed a series of work-sheets *seriatim* to the cylinder and feed roll, of a swinging frame carrying said roll, a cam to move said frame into position to hold the roll against the cylinder, a holding latch to hold the cam in said position, a trip arm to release the latch, means geared to the cylinder to actuate the trip arm during each rotation of the cylinder, means connected with the cylinder to restore said cam to position to hold the roll against the cylinder and to cause the latch to be restored to holding position, and a deflecting device to deflect said trip arm and extending into the path of the advancing work-sheets, whereby said trip arm is deflected by the work-sheets and prevented from releasing the latch during a normal supply of work-sheets to the cylinder and feed roll.

3. In a stenciling machine, the combination with a stencil cylinder and a feed roll running thereon, of mechanism comprising a latch for holding the feed roll against the cylinder, sheet-feeding devices geared to the cylinder to receive one complete rotation and advance a work-sheet each time the cylinder is rotated, an eccentric connected to rotate in unison with the stencil cylinder, a trip arm connected to said eccentric, and movable thereby into position to trip said latch, and a deflector connected to said trip arm and extending into the path of the work-sheets and operable thereby to deflect the trip arm to inoperative position.

4. In a stenciling machine, the combination with a stencil cylinder and a feed roll, of sheet-feeding mechanism to advance work-sheets to said cylinder and roll, a latch to hold the feed roll on the cylinder, a trip device controlled by the work-sheets and operable to automatically trip the latch and thereby permit the feed roll to move from the cylinder when the supply of work-sheets fails, and means to automatically restore the feed roll and latch to operative position when work again passes.

5. In a stenciling machine, the combination with a stencil cylinder and a feed roll, of a latch and means coöperating therewith to hold the feed roll against the cylinder, means to release said latch, and a cam connected to the cylinder and operable at a predetermined period in the rotation of the cylinder to restore the latch coöperating means.

6. In a stenciling machine, in combination with a stencil cylinder and a feed roll, of sheet-feeding mechanism, mechanism comprising

a latch and mechanism coöperating therewith, for holding the feed roll in operative position, a trip to release said latch, means operable by the advancing work-sheets to maintain said trip in ineffective position, and a cam rotatable with the cylinder to automatically restore said latch coöperating mechanism.

7. In a stenciling machine, in combination with a stencil cylinder and a feed roll, of means to move the feed roll away from the cylinder, a cam rotating with the cylinder, a holding device in the path of the cam and operable thereby to move the feed roll into engagement with the cylinder, a latch to engage and hold said device when the feed roll is against the cylinder, a trip to release said latch, and means actuated by the advancing work-sheets to move the trip to ineffective position, whereby the latch is permitted to hold the feed roll against the cylinder while the work-sheets are being fed thereto and said latch is released to permit separation of the feed roll from the cylinder when the supply of work-sheets fails.

8. In a stenciling machine in combination, a stenciling cylinder and a feed roll coöperating therewith, means for feeding sheets one by one between the two, pivot arms to carry said feed roll, means for moving said arms to bring the feed roll into operative position in relation to the stencil cylinder, a latch to hold said supporting arms with the feed roll in operative position, a roll geared to said stencil roll and means on the geared roll to occasion withdrawal of the supporting arms when a sheet fails to pass.

9. The combination with a rotary cylinder and a feed roll running thereon, of means for feeding sheet material to said cylinder and roll, a supporting device for said roll, a latch to hold said device in position to hold the roll against the cylinder, an intermittently operated trip adapted at each operation to trip the latch and permit said roll to be separated from the cylinder, means to automatically restore the latch and roll, and means on the cylinder shaft operated by the sheet material to deflect said trip at each operation of the trip to an ineffective position, whereby the release of the latch is prevented during the normal feeding of the sheet material to the cylinder, the tripping of the latch being permitted when there is a lapse in the supply of sheet material to the cylinder.

10. The combination with a rotary cylinder and a feed roll, of means for feeding work-sheets to said cylinder and roll, means to support the feed roll, a latch normally holding said supporting means in position to retain the feed roll in running contact with the cylinder, a latch-releasing trip, means to intermittently operate the trip for

releasing the latch, means operated by the advancing work-sheets to render the operation of the trip ineffective to release the latch during the normal supply of work-sheets to the cylinder, and a cam to return said supporting means to operative position, and permit the restoration of the latch, said cam being brought intermittently to operative position in alternation with the operation of the trip-operating means.

11. The combination with a printing surface and a feed roll, of means to feed a sheet between said roll and printing surface, a latch holding said roll against the printing surface, said roll, when unrestrained by the latch, being movable away from the printing surface, a trip operated intermittently to release the latch and permit the separation of the roll from the printing surface, means to automatically restore the roll to the printing surface, and means controlled by the work-sheets to prevent said trip when operated from releasing the latch.

12. In a stenciling machine, the combination with a stencil cylinder and a feed roll, of mechanism for feeding work-sheets *seriatim* to said cylinder and roll, a latch to hold the feed roll against the cylinder, a trip to release said latch and permit the feed roll to separate from the cylinder, means to actuate said trip during each rotation of the cylinder, means actuated by the work-sheets to automatically deflect said trip to ineffective position, and means to automatically restore the roll and latch to operative position after the latch has been released by said trip.

13. In a stenciling machine, the combination with a stencil cylinder and a feed roll, of mechanism for feeding work-sheets *seriatim* to said cylinder and roll, a latch to hold the feed roll against the cylinder, a trip for said latch, means to reciprocate said trip during each rotation of the cylinder, a rock shaft, a rod connected to said rock shaft and projecting into the path of the advancing work-sheets, and means carried by the rock shaft to deflect the trip to an ineffective position when the work-sheets are advanced, so that the reciprocation of the trip is effective to release the latch only when there is a lapse in the advance of the work-sheets.

14. The combination with a revoluble stencil cylinder and a feed roll to run on said cylinder, of a device for supporting the feed roll and holding it against the cylinder, said feed roll automatically movable away from the cylinder when not restrained by said holding device, a latch to hold said device in operative position with the roll against the cylinder, a sheet-feeding device geared to operate in unison with the stencil cylinder and operative to feed sheets *se-*

riatim to the cylinder, one sheet being advanced to the cylinder at each revolution of the latter, a trip device driven in unison with the cylinder and actuated at each rotation of the cylinder, said trip device operable to release said latch, and trip-controlling means to control the trip and prevent the release of the latch during the normal supply of the work-sheets, and permit the trip to operate the latch upon failure of the sheet-feeding device to advance a work-sheet.

15. The combination with a revoluble stencil cylinder and a feed roll to run on said cylinder, of a device for supporting the feed roll and holding it against the cylinder, said feed roll automatically movable away from the cylinder when not restrained by said holding device, a latch to hold said device in operative position with the roll against the cylinder, a sheet-feeding device geared to operate in unison with the stencil cylinder and operative to feed sheets *seriatim* to the cylinder, one sheet being advanced to the cylinder at each revolution of the latter, a trip device driven in unison with the cylinder and actuated at each rotation of the cylinder, said trip device operable to release said latch, trip-controlling means to control the trip and prevent the release of the latch during the normal supply of the work-sheets, and permit the trip to operate the latch upon failure of the sheet-feeding device to advance a work-sheet, and a restoring cam rotatable in unison with the cylinder and operable to return said feed-roll-supporting device to operative position and cause the latch to be restored to holding position after it has been released by the trip, said cam running free of said feed-roll-supporting device while the feed roll is running on the cylinder.

16. The combination with a rotary stencil cylinder and a feed roll beneath said cylinder, of a supporting device to hold said feed roll up to the cylinder, a latch to hold the supporting device in operative position, a trip operative to release the latch and permit the feed roll to drop away from the cylinder, a work-sheet-feeding device geared to the cylinder and operable in unison therewith to advance a work-sheet to the cylinder at each revolution of the latter, said trip geared to the cylinder and actuated at each revolution of the cylinder, and trip-controlling means to render the trip ineffective when work passes.

17. In a printing device, a rotary printing couple, means for feeding sheets to said couple, horizontally pivoted arms, one member of said couple being mounted in said arms to swing vertically toward and from the other member, a roller on said arms, a rock shaft, a cam on said rock shaft adapted

to engage said roller, an arm on said rock shaft, an upwardly extended rod connected to said arm, a notch in said rod, a latch engaging said notch and a trip operative unless a sheet passes to release said latch and permit the disengagement of the printing couple.

18. In a printing machine in combination, a printing couple, one member of said couple being mounted in fixed bearings, and the other in retractile bearings, means for holding the two members in printing relation, said means including a latch, a gear wheel mounted on the shaft of the member in fixed bearings, a second gear wheel in gear with said first mentioned gear wheel, an eccentric on said second gear wheel, a ring mounted on said eccentric, an arm depending from said ring, a rock shaft in line with the shaft of the eccentric carrying gear wheel and in frictional engagement therewith, a downwardly extending guide rod on said rock shaft, said guide rod and said arm being in sliding engagement, a latch having a slot 25 through which said guide rod may go when no work passes, and an arm on said latch

adapted to be engaged by said ring arm when no work passes.

19. In a printing machine in combination, a printing couple, one member of said couple being mounted in fixed bearings and the other in retractile bearings, means for holding the two members in printing relation, said means including a latch, a gear wheel mounted on the shaft of the member in fixed bearings, a second gear wheel in gear with said first mentioned gear wheel, an eccentric on said second gear wheel, a ring mounted on said eccentric, an arm depending from said ring, guiding and retracting means in engagement with said arm, an arm on said latch in the normal downward path of movement of said ring arms when no work passes, and means whereby said ring arm is deflected from its normal 40 downward path of movement when work passes so as to avoid the latch arm.
